UNITED STATES PATENT OFFICE

147,472

DESIGN FOR A MOTORIZED SCOOTER

Jimmie H. Reed, Detroit, Mich.

Application October 22, 1945, Serial No. 123,063

Term of patent 7 years

(Cl. D90—8)

To all whom it may concern:

Be it known that I, Jimmie H. Reed, citizen of the United States, residing at Detroit, in the county of Wayne and State of Michigan, have invented a new, original, and ornamental Design for Motorized Scooters, of which the following is a specification, reference being had to the accompanying drawing, forming part thereof.

In the drawing:

Fig. 1 is a side perspective view of a motorized scooter, showing my new design;

Fig. 2 is a front elevational view showing the motorized scooter of my design;

Fig. 3 is a rear elevational view showing the motorized scooter of my new design; and

Fig. 4 is a top plan view thereof.

I claim:

The ornamental design for a motorized scooter, as shown.

JIMMIE H. REED.
